UNITED STATES PATENT OFFICE.

JACQUES WORTH, OF PARIS, FRANCE.

DESIGN FOR A BOTTLE.

Application filed October 3, 1925. Serial No. 15,016. Term of patent 7 years.

To all whom it may concern:

Be it known that I, JACQUES WORTH, a citizen of France, residing at Paris, in the Republic of France, have invented a new, original, and ornamental Design for Bottles, of which the following is a specification, reference being had to the accompanying drawing, forming part thereof.

In the drawing: The figure is a perspective view.

I claim:

The ornamental design for a bottle as shown.

JACQUES WORTH.
